SUN REFLECTOR FOR SKIN TANNING

Nicki L. Mussé, San Francisco, Calif.

Application April 18, 1955, Serial No. 35,555

Term of patent 14 years

(Cl. D83—1)

FIG-1

FIG-2

FIG-3

FIG-4

Fig. 1 is a perspective view of a sun reflector for skin tanning showing my new design.

Fig. 2 is a top plan view thereof.

Fig. 3 is a side elevational view thereof.

Fig. 4 is a rear elevational view thereof.

I claim:

The ornamental design for a sun reflector for skin tanning, as shown.
